UNITED STATES PATENT OFFICE.

THOMAS HARDING, OF NEWARK, NEW JERSEY, ASSIGNOR TO J. L. SOMMER MANUFACTURING CO., A CORPORATION OF NEW JERSEY.

DESIGN FOR A BOTTLE-OPENER AND PICK.

46,311.

Specification for Design.

Patented Aug. 25, 1914.

Application filed June 25, 1913. Serial No. 775,805. Term of patent 14 years.

To all whom it may concern:

Be it known that I, THOMAS HARDING, a citizen of the United States, residing at Newark, in the county of Essex and State of New Jersey, have invented a new, original, and ornamental Design for a Bottle-Opener and Pick, of which the following is a specification, reference being had to the accompanying drawing, forming part thereof.

Figure 1 is a side view of a combined bot-

tle opener and pick, showing my new design, and Fig. 2 is an edge view of the same.

I claim:

The ornamental design for a combined bottle opener and pick, as shown.

THOMAS HARDING.

Witnesses:

LEILA C. GOULD,
CHAS. MUNTRICK.
